UNITED STATES PATENT OFFICE

ABRAHAM WEISS, OF NEW YORK, N. Y.

LOCKING DEVICE FOR MOTOR VEHICLES

Application filed August 24, 1928. Serial No. 301,846.

The present invention relates to motor vehicles. It frequently happens that when the vehicle stops in heavy traffic a person runs up to the vehicle and in an attempt to enter the same either to steal a ride or because of being in a hurry, opens the door without first notifying the driver. If at the moment the door is opened the vehicle is set in motion an accident may result to the prospective 10 rider. Accidents also often happen which result in injury to passengers or to the vehicle as a result of the door being open while the vehicle is in motion.

The object of this invention is to prevent 15 such accidents or damage, which I accomplish according to the present invention by electrical means so arranged between the door of the vehicle and other parts of the machine that when the door is open and an attempt is 20 made to run the car the motor will stop.

A further object is to so arrange my device that the engine will run idle even though the door be open but will stall immediately 25 when any attempt is made to drive the machine, either by depressing the accelerator, shifting the gear or other similar starting operations.

Other objects will appear from the detailed 30 description to follow.

In the accompanying drawings in which 35 similar reference characters denote corresponding parts Fig. 1 is a side view of a vehicle partly in section showing my new device associated with a door and the accelerator of the vehicle; Fig. 2 shows the details 40 of the electrical circuit and the method of associating my device with the gear shifting mechanism and Fig. 3 shows a further modification wherein I associate my circuit with the transmission shaft.

10 denotes a motor vehicle of any type or construction employing for instance a high tension spark device 11 to produce ignition. 12 denotes the usual gas feed accelerator on the vehicle and 13 denotes a door of the vehicle. 14 denotes a switch adapted to be controlled from the accelerator and having contact points 14' and 14² so arranged that when the accelerator 12 is undepressed 50 or in idle position a bridging contact mem-

ber 14³ attached to the accelerator 12 will only contact with member 14'. Immediately however that said accelerator 12 is depressed the member 14³ will bridge both contact points 14' and 14². 15 denotes the wall 55 of the vehicle to which the door 13 is hinged. Between the opposite edges of the door 13 and said wall 15 I provide a switch which according to the present embodiment is constructed as follows:

In a groove provided in the wall 15 is mounted a cylindrical casing 18 of insulating material the outer open end of which is closed by an annular member 19 of conductive material. Slidably mounted in the cylinder 18 is a disc 20 of conductive material which is actuated by a spring 21 one end of which is fixed to the inner face of said disc 20 and the other end to a plate 22 of conductive material provided with an electrical connection 23 projecting through the cylinder 18. The outer face of said disc 20 has screwed or otherwise fixed to it a slug or pin 24 of non-conductive material which projects through and is guided in the annular member 19. 60 65 70 75

The spring 21 tends when the door is open to force the pin 24 outwardly and hold the disc 20 in contact with the inner face of member 19. When the door is closed its edge 13' will depress the plug 24 and as a result thereof move the disc 20 out of contact with member 19. The disc 22 and its lead 23 constitute one of the terminals of switch and is connected to ground by wire 25. The member 19 is connected by a wire 26 to one of the contact points as 14' of switch 14 and the second contact point 14² is connected by wire 27 to one of the interrupter points 11' of the high tension spark device 11. The other 80 85 90 point 11² is connected to ground.

It will be clear then that when the door of the vehicle is open the door switch will close. However, nothing else will happen yet. As soon however as the operator attempts to speed up the engine by depressing the accelerator then the bridging contact member 14³ will close the circuit through the contact points 14' and 14² and short circuit the interrupter points 11' and 11² through the ground 95 100

thus stalling the engine. It will be noted particularly that the mere act of opening the door without depressing the accelerator will not stall the engine. It is only when an actual attempt is made to start the car moving that the short circuiting of the ignition system will take place.

It is of course possible to arrange my system with other elements in the mechanism necessary to drive the car. For instance I can associate it with the gear shift mechanism as is shown in Fig. 2 of the drawings wherein the high tension ignition device 11 and the door switch are the same as before. In place of the accelerator switch 12 I attach such switch mechanism to the gear shift mechanism. 28 represents the gear shift casing in which are the sliding rods 29, which communicate with gears in the transmission system. Each of said rods is provided with an enlarged portion having slotted portions 29' on their inner faces for the engagement of the usual movable gear shift lever 30 whereby each of the rods 29 may be moved forward or backward to shift the gears to the desired position. Provided at the outer faces of said rods 29 are contact projections 31 which are designed to contact with contact members 32, insulatively mounted by means of insulation members 33 on the gear casing 28, when either of the rods 29 are shifted forward or backward. The members 32 are connected in parallel by wires 32' so that when either of the rods 29 are shifted forward or backward, the same electric circuit may be closed, and when the gears are in neutral position open circuit is obtained. This switch mechanism may be connected as shown in Fig. 2 the casing 28 being connected to ground by wire 32' and being directly in contact with rods 29 is also connected to switch points 31. Contact members 32 are connected by wires 32' to plate 22 by wire 26' and connection 23, thence plate 19 is connected by wire 27' to contact 11' of the ignition device and contact 11² thereof is grounded. When the door is opened, door switch 19 is closed. Then any attempt to shift gears closes the circuit through contacts 31 and 32 short circuiting the points 11' and 11² and stopping the engine.

In another modification shown in Fig. 3 the gear shift switch is replaced by a switch arranged on the transmission rod of the machine. Provided on the transmission shaft 34 of engine 35 is a governor arrangement having contacts 36 arranged to contact with stationary contact 37 when the speed of the shaft 34 is such as to cause said contacts 36 to spread out. Thus the short circuit across the ignition device 11 is accomplished by the closing of the switch points 36 and 37 when the transmission shaft is speeded up on starting of the machine.

It is of course possible to have my elec-

trical control affect points in the ignition system other than the interrupter points of the ignition device without departing from the spirit of my invention and it is obvious that my invention may be modified in various other ways and I do not wish to be limited to the modifications shown and described.

For instance I may provide auxiliary switches in the circuit of my system whereby if it is used with a taxicab it will be impossible to run the machine without a passenger in the rear and the flag of the taximeter down, or vice versa.

What I claim is:

1. In a motor vehicle having driving control means, a door and an electrical fuel ignition system, a switch controlled through said door, a switch controlled through said driving control means and series electric connections between said switches across the ignition system such that when the door is open and the driving control is placed in operative position the ignition system will be short circuited.

2. In a motor vehicle having driving control means, a door and an electrical fuel ignition system, a switch controlled by said door and adapted to be closed electrically when said door is open, a second switch controlled by said driving control and adapted to be closed electrically when said driving control is in operative position, series electrical connection between said switches across the ignition system whereby when said door is open and said driving control is placed into operative position said ignition system will be short circuited.

3. In a motor vehicle having a gear shift mechanism, a door and an electrical fuel ignition system, a switch controlled by said door, a switch controlled by said gear shift mechanism and adapted to be closed in all positions but neutral, an electric connection between said switches across the ignition system such that when said door is open and said shift mechanism is moved out of neutral, said ignition system will be rendered ineffective.

4. In a motor vehicle having a transmission shaft, a door and an electrical fuel ignition system, a switch controlled through said door, a switch controlled by said transmission shaft and adapted to close when said transmission shaft is speeded up on starting of the vehicle and an electric connection between said switches across the ignition system such that when said door is open and said shaft is speeded up said ignition system will be rendered ineffective.

5. In a motor vehicle having an accelerator, a door and an electrical fuel ignition system, a switch controlled through said door, a switch controlled by said accelerator and adapted to close when the latter is actuated and an electric connection between said

switches across the ignition system such that when said door is open and said accelerator is actuated said ignition system will be rendered ineffective.

5 In testimony whereof I affix my signature.
